UNITED STATES PATENT OFFICE

2,419,654

PASTRY DECORATOR

William V. Moore, Chicago, Ill.

Application April 27, 1945, Serial No. 590,691

1 Claim. (Cl. 107—52)

1

This invention relates to a pastry decorator, and has for one of its objects the production of a simple and efficient means for decorating pastry, garnishing steaks, and the like, in a manner whereby the design of a rose, flower, or other selected configuration, may be cast or ejected from the nozzle or cap in one operation.

A further object of this invention is the production of a simple and efficient nozzle or cap which is provided with a concavo-convex design-forming portion having material-ejecting slots arranged therein for the purpose of casting or forming a complete design in depth by one operation.

Other objects and advantages of the present invention will appear throughout the following specification and claim.

In the drawing—

Figure 1 is a side elevational view of the decorator;

Figure 2 is a fragmentary enlarged side elevational view of the ejector end of the decorator;

Figure 3 is a vertical sectional view of the nozzle or cap;

Figure 4 is an end view of the nozzle or cap;

Figure 5 is a perspective view of one form of design cast or formed by the decorator;

Figure 6 is a top plan view of the design shown in Figure 5;

Figure 7 is a side elevational view of the design shown in Figures 5 and 6;

Figure 8 is an end view of a modified design of nozzle;

Figure 9 is an end view of a further modified design of nozzle.

By referring to the drawing it will be seen that 10 designates the conventional bag which is used with the pastry decorator, and which bag may be formed of rubberized material, light weight canvas, or the like, the bag 10 tapering toward its ejecting end as shown in Figure 1. A nozzle 11 is carried by the ejecting end of the bag or container 10, and this nozzle 11 is provided with a funnel-like entrance end 12 for receiving material from the bag, the ejecting end of the bag 10 fitting snugly over the funnel-like portion 12 in the manner shown in Figure 2, and being secured thereto in any suitable or desired manner.

The outer discharge end of the nozzle 11 is provided with an external neck 13 upon which externally threaded neck 13 is threaded an internally threaded cap 14. This cap 14 comprises an annular flange 15 which fits in threaded engagement with the neck 13 for detachably securing the cap 14 to the neck 13. The cap 14 is provided

2

with an inwardly pressed or formed concavo-convex design-forming portion 16, in which design-forming portion 16 are formed the design-forming slots 17, these slots being arranged in a suitable or selected design for the purpose of producing rose bud, a part-bloom rose, or a full-blown rose, or any suitable selected flower or other design.

The cap 14 is detachable upon the neck 13 10 as specified above so that the cap may be replaced for the purpose of casting other selected designs when desired. It is important to note, however, that the cap 14 is essentially provided with the inwardly formed or extending design-forming 15 portion 16, the slots 17 extending entirely through the portion 16 as shown, so that the material such as frosting, potatoes, or other selected material used in decorating cakes, pies, garnishing steaks, and the like, may be easily ejected through 20 the slots 17 as the bag 10 is compressed in the conventional manner. The arrangement of the slots 17 shown in Figure 4 will produce a design such as is illustrated in Figures 5 and 6 simulating a rose. In operation the cap 14 is placed 25 against the surface upon which the design is to be formed and the bag 10 is compressed to force the paste material, mashed potatoes, or the like, out through the slots 17 of the cap 14. Then by merely lifting the entire device including the cap 14 away from the ejected material, this movement will cause the petals of the flower such as a rose to be formed in a natural appearing petal formation such as is illustrated in Figures 5 and 6.

It should be understood that the important 35 feature of the present invention is the formation of the desired design in one operation and without the necessity of complicated and artistic manipulation and practice. The design of the petals will be formed by the arrangement of the slots 17 in the cap 14 and no expert manipulation is required, and it is only necessary to compress the bag once to eject the material through the slots 17, and to then release the pressure and lift the cap 14 with the bag away from the formed 40 design, leaving the design properly and artistically formed in depth with a proper thickness or substance of material to give the appearance of a rose or other flower, or of any other selected 45 design.

In Figure 8 an arrangement of slots is shown upon the cap 14^a for casting a rose bud, and the arrangement of slots shown upon the cap 14^b in Figure 9 will form a part-bloom rose.

It should be understood that the design may be varied without departing from the spirit of the

invention and that the present construction is adapted for use in casting or forming designs, decorations, and the like of various types other than flowers and roses as illustrated for example in Figures 5 and 6. One important element of the present invention is the arrangement of the concavo-convex design-forming portion of the cap as well as the arrangement of the slots 17 which, in conjunction with the applied pressure upon the material ejected through the slots will make possible the formation of the desired artistic and natural appearing design possessing a natural contour along the top surface and upper edges of the petals of a flower—note Figure 7. This is accomplished solely by one operation and the concave under face of the design-forming portion produces this natural appearing contour upon the top face of the formed design wherein the central portion of the bud, flower and the like, is higher than the side or marginal petals thereof.

It should be understood that the device may be varied in its shape, contour or arrangement of slots without departing from the spirit of the invention and that the cap 14 together with its design-forming portion 16 may be shaped in any desired manner to form the selected design. The present device may be used in any size or shape and may be used for molding any type of material, food, and the like, such as candy, ice cream, where decorations and fanciful molds are desired. The cap 14 as well as the nozzle 11 may be formed of plastic, metal, or any suitable type of rigid material.

Certain detail changes in the construction may be employed without departing from the spirit of

15
15 the invention, so long as such changes fall within the scope of the appended claim.

Having described the invention, what is claimed is:

5 As an article of manufacture, a design-forming cap comprising a design-forming bottom wall and a bottom edge, the bottom wall being inset and curved inwardly in concave formation relative to said bottom edge, said wall having spaced design-forming slots formed therein, some of the slots being located inwardly toward the center of the bottom wall relative to the bottom edge and inwardly relative to other of said slots and being located in various elevated planes to produce a dome-like design having petals of various heights increasing in height from the edge toward the center of the designed material which is formed by forcing material through said slots.

20 WILLIAM V. MOORE.
